UNITED STATES PATENT OFFICE

1,965,430

VEHICLE ACTUATED TRAFFIC SIGNAL

Justin Peterson, Lynn, Mass., assignor to General
Electric Company, a corporation of New York

Application April 12, 1932, Serial No. 604,741

2 Claims. (Cl. 177—329)

The present invention relates to traffic signals of the type comprising a treadle located in the roadway which, when a vehicle passes over it, closes an electric circuit to effect actuation of the 5 lamps or other devices which signal to traffic the right of way.

The object of my invention is to provide an improved construction and arrangement in apparatus of this type, and for a consideration of 10 what I believe to be novel and my invention, attention is directed to the following specification and the claims appended thereto.

In the drawing, Fig. 1 is a diagrammatic view of a road intersection provided with a traffic actuated signalling arrangement; Fig. 2 is a transverse sectional view of a treadle, and Fig. 3 is a wiring diagram.

Referring to Fig. 1 of the drawing, 1 indicates a road intersection provided with a signalling device 2 of any suitable type for directing traffic through the intersection. It may comprise, for example, red, amber and green signal lights arranged to be operated to direct traffic along the traffic lanes which are indicated E, W, N and S. 20 Located in each traffic lane at its right hand side is a vehicle actuated device or treadle 3, one of which is shown in section in Fig. 2. Vehicle actuated devices 3 are connected by cables indicated at 4 to a control box 5 in which is located suitable mechanism for controlling the signal lights 2 to which it is connected by a cable indicated at 6. A portion of the signal mechanism contained in casing 5 comprises parts shown in Fig. 3 as hereinafter described.

Referring to Figs. 2 and 3, the vehicle actuated device 3 comprises an electrical condenser A of suitable capacity embedded in the roadway and adapted to have its capacitance varied by a vehicle passing over it. It may comprise two or 30 more metal plates 7 suitably spaced apart and embedded in a rubber envelope or casing 8 which in turn may be held in a metal casing 9. 10 indicates the bed of the roadway. When a vehicle passes over the device, its wheels will depress the rubber casing, moving plates 7 closer together and thus changing the capacitance of the device.

Electrical condenser A is connected by conductors 11 and 12 to a source of alternating current 13, here shown as the secondary winding of a 40 transformer. In circuit with it is a condenser B of fixed capacity, condenser B being in balanced relation to condenser A and having a capacity such that normally the two condensers substantially balance each other.

Connected in circuit with the condensers is a

relay device 14 for effecting actuation of control mechanism for the signals 2. The details of the control mechanism for the signals is not shown as its specific structure forms no part of the present invention. For the purposes of this invention it 50 may be taken to comprise circuit 15 which is opened when relay device 14 is energized, opening of such circuit serving to set into operation any suitable timing mechanism for the signals. The relay device is connected to the condensers 60 through an electric valve 16 which serves as a relay controlling the circuit of the winding 17 of relay device 14. To this end winding 17 has one terminal connected by a conductor 18 through a source of alternating current supply 19 to the filament 20 of the electric valve and the other terminal connected to the plate 21 of the electric valve. The filament heating circuit is indicated at 22. Grid 23 is connected by a conductor 24 to a point between the variable condenser A and 70 the fixed condenser B. A resistance 25 may be provided on this circuit to prevent high currents from flowing therein.

With the described arrangement, the variable condenser A and the fixed condenser B tend to 80 balance one another so far as the grid voltage on the electric valve is concerned. The capacitance of the fixed condenser is of a value such that there is a slight unbalance between it and the capacitance of the traffic actuated condenser in 85 a direction such that there is a negative voltage applied to grid 23 which prevents current flowing between the filament and the plate. When a vehicle passes over the vehicle actuated device, the plates 7 of the condenser are moved closer 90 together due to the weight of the vehicle depressing the casing 8 thereby increasing the capacitance of the condenser A and effecting an unbalance between the two condensers A and B in 95 a direction such that positive voltage is applied to grid 23. Current will now flow in the plate circuit, energizing relay winding 17 and opening the circuit through conductor 15 to effect an actuation of the control mechanism for the signals 2.

As soon as the pressure on the vehicle actuated device is released, negative voltage is again applied to grid 23 thereby stopping flow of current in the plate circuit and deenergizing relay 14.

By my invention, I provide a vehicle actuated device which is simple in structure and entirely enclosed in a casing so as to be protected from the weather. Also, I avoid the use of contacts which must be moved into engagement with each other. This results in a vehicle actuated device 110

which is reliable in operation and not likely to get out of order.

In accordance with the provisions of the patent statutes, I have described the principle of operation of my invention, together with apparatus which I now consider to represent the best embodiment thereof, but I desire to have it understood that the apparatus disclosed is only illustrative and that the invention may be carried out with such modifications as come within the scope of the appended claims.

What I claim as new and desire to secure by Letters Patent of the United States, is:

1. In combination, a vehicle-actuated device including a condenser mounted at a highway intersection in the path of vehicles and provided with plates resiliently mounted with respect to each other and arranged to change the capacity

of said condenser when compressed by vehicles approaching said intersection, a traffic-signalling unit, and means responsive to such change in the capacity of said condenser for operating said signalling unit for indicating the right of way to vehicles causing said change in capacity.

2. In combination, a traffic-signalling unit arranged to control traffic at the intersection of a plurality of traffic lanes, vehicle-responsive means located in each of said traffic lanes including a condenser arranged to change its capacity when compressed by a vehicle, and means responsive to said change in capacity including an electric-discharge valve connected between said condenser and said signalling unit to operate said signalling unit to give the right of way to the lane of said condenser.

JUSTIN PETERSON.
